Primary Examiner — Marianne Pandozzi(74) Attorney, Agent, or Firm — Michael J. Gallagher; David J. Dawsey; Gallagher & Dawsey Co., LPA(57) CLAIM

I claim the ornamental design for a racing helmet themed beverage dispenser, as shown and described.

DESCRIPTION

FIG. 1 is a left side isometric view of a racing helmet themed beverage dispenser showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings are included for the purpose of illustration and forms no part of the claimed design.
